(57) **CLAIM**

The ornamental design for a cup and base set, as shown and described.

DESCRIPTION

FIG. 1 is an exploded perspective view of a cup and base set showing my new design;

FIG. 2 is a perspective view thereof;

FIG. 3 is a sectional view taken along line F-F of FIG. 2;

FIG. 4 is a sectional view taken along line S-S of FIG. 2;

FIG. 5 is an exploded front elevational view thereof, the rear elevational view being identical;

FIG. 6 is an exploded side elevational view thereof, the opposite side elevational view being identical;

FIG. 7 is a bottom plan view of the cup portion only, the base removed for ease of illustration;

FIG. 8 is a bottom plan view of the cup and base set (the bottom of the base) of embodiment 1;

FIG. 9 is a top plan view of the cup and base set (the top of the cup) of embodiment 1;

FIG. 10 is a top plan view of the base only, the cup removed for ease of illustration;

FIG. 11 is a perspective view of a cup and base set showing a second embodiment of my new design in a transparent version;

FIG. 12 is an exploded front elevational view thereof, the rear elevational view being identical;

FIG. 13 is an exploded side elevational view thereof, the opposite side elevational view being identical;

FIG. 14 is a bottom plan view of the cup portion only, the base removed for ease of illustration;

FIG. 15 bottom plan view of the cup and base set (the bottom of the base) of embodiment 1;

FIG. 16 a top plan view of the cup and base set (the top of the cup) of embodiment 1; and,

FIG. 17 a top plan view of the base only, the cup removed for ease of illustration.
